(57) **CLAIM**

The ornamental design for a display screen with animated graphical user interface, as shown and described.

DESCRIPTION

FIG. 1 is a front view of a display screen with animated graphical user interface showing a first image of our new design; and,

FIG. 2 is a front view of a second image thereof.

The appearance of an image sequentially transitions to another between FIG. 1 and FIG. 2. The process or period in which an image transitions to another forms no part of the claimed design.

The outer peripheral solid lines in the figures show a display screen, or portion thereof. The broken lines depict portions of the graphical user interface that form no part of the claimed design.
